(57) **CLAIM**

The ornamental design for the forge ice press, substantially as shown and described.

DESCRIPTION

FIG. 1 is a perspective view illustrating ornamental features of the forge ice press;

FIG. 2 is side view thereof;

FIG. 3 is another side view thereof;

FIG. 4 is an opposing side view (relative to FIG. 2) thereof;

FIG. 5 is an opposing side view (relative to FIG. 3);

FIG. 6 is a top view thereof; and,

FIG. 7 is a bottom view thereof.

The lines indicating shading in FIGS. 1-7 are for illustrative purposes only and form no part of the claimed design.
